UNITED STATES PATENT OFFICE.

GEORGE C. KNAUFF, OF CHICAGO, ILLINOIS, ASSIGNOR TO EDMUNDS & JONES CORPORATION, OF DETROIT, MICHIGAN, A CORPORATION OF NEW YORK.

SWITCHING-SOCKET.

1,285,739.

Specification of Letters Patent. Patented Nov. 26, 1918.

Application filed January 15, 1917. Serial No. 142,348.

To all whom it may concern:

Be it known that I, GEORGE C. KNAUFF, citizen of the United States, residing at Chicago, in the county of Cook and State of Illinois, have invented certain new and useful Improvements in Switching-Sockets; and I do hereby declare the following to be a full, clear, and exact description of the invention, such as will enable others skilled in the art to which it appertains to make and use the same.

My invention relates to electric sockets or connectors, its general objects being to provide simple, compact and effective switching means for connecting and disconnecting the circuit in a double-pole socket or connector. In my issued Patent No. 1021195, dated March 26, 1912, I have shown and described a double-pole switching socket in which the controlling of the circuit is effected by partially rotating an insulating body mounted in the socket casing, so as to bring two compressible conductors carried by this insulating body respectively into or out of contact with the terminals of a lamp or other terminal-carrier. My present invention aims to produce the same result by moving an insulating body longitudinally of the socket casing, so as to bring the conducting elements mounted on this body respectively into or out of contact with conducting elements on terminal-carriers held rigid with respect to the socket casing. My invention also aims to provide spring-pressed extensions for certain of the conducting elements, so that the circuit-connections at one end of the movable insulator are maintained continuously, and preferably also aims to utilize the pressure of such spring-actuated elements for maintaining one or more of the constituents of the socket or connector in operative position regardless of the jarring to which the appliance may be subjected.

Still other objects will appear from the following specification, and from the accompanying drawings, in which drawings—

Figure 1 is a central longitudinal section through a lamp-socket embodying my invention, showing the switching member in its "off" position, or interrupting the circuit.

Fig. 2 is a fragmentary view showing the switching member in its "on" position.

Fig. 3 is a view, partly in section, showing a switching member inverted in operative

position from that of the embodiment of Fig. 1.

Fig. 4 is a fragmentary view showing an embodiment in which the switching member carries incompressible conducting elements and in which the wire-terminal plug has terminals equipped with spring pressed extensions.

In the embodiment of Fig. 1, the socket of my invention includes a cylindrical casing 1 equipped at one end with bayonet catch 65 formations 2 for interlocking with pins 3 on the base of a lamp 4. Mounted in the other end of the casing and secured thereto by a rivet 5, is an insulating plug 6 carrying two wire terminals 7, which terminals aline longitudinally of the socket with the terminals 8 of the lamp. Slidable within the casing between the lamp 4 and the plug 6 is an insulator 9 carrying two conducting members, which members extend longitudinally 75 of the casing and aline respectively with one each of the terminals on the plug and the lamp. Each of the said conducting members consists desirably of a metal cylinder 10 housing a portion of a plunger 11, which 80 plunger projects beyond one end of the cylinder and continuously contacts with one of the terminals 8 of the lamp, each plunger being continuously pressed toward the lamp by a compression spring 12 also housed by 85 the adjacent cylinder 10. Fast upon the insulator 9 is a handle 13, which handle projects through a substantially hook-shaped slot 14 in the socket casing, the hook formation of the slot presenting its bend toward 90 the lamp end of the casing and the shorter arm of said slot being so located as to afford a seat for the handle when the insulator 9 is in the position of Fig. 1; that is to say, when the insulator is raised so as to bring the 95 closed ends of the cylinders 10 out of contact with the terminals on the plug. When thus raised, the plungers 11 are forced for a considerable distance into the cylinders 10 against the pressure of the springs 12, and 100 these springs through the plungers and the handle 13 serve to hold the lamp and the insulator 9 firmly interlocked with the casing. Consequently, any jarring of the socket, such as is common with appliances 105 used upon automobiles, will not interfere with the firm maintaining of both the lamp and the slide in the position shown.

Upon raising the handle 13 to move it beyond the bend of the hook-shaped slot, the pressure of the spring-actuated plungers will force the insulator 9 downward into the position of Fig. 2, so that the cylinder ends will contact with the plug terminals while the plungers will continue to contact with the lamp terminals. In this position, the spring-pressed plungers also will hold the pins 3 on the lamp base firmly interlocked with the bayonet catch slot formations on the socket casing, so that with this construction the lamp will be rigidly held at all times.

15 However, I do not wish to be limited to the use of plungers or conductor extensions) projecting toward the lamp terminals, nor to this particular form of extensible conductors on the insulator 9 (which insulator, together with the compressible conducting members carried by it, forms the slide or switching member of my appliance), nor to other of the details as above disclosed. Obviously, the construction and arrangement might be modified in many ways without departing from the spirit of my invention. For example, the conducting members on the slide may be inverted, as shown in Fig. 3, so that the plunger ends 20 will press against the plug terminals continuously while a downward movement of the slide will bring these conducting members out of contact with the lamp terminals. Or, the spring-pressed extensions or plungers may be mounted on the plug terminals, as in Fig. 4, in which latter case the conducting elements 15 on the insulator 9 may merely be solid cylinders of brass. With the inverted arrangement of Fig. 3, it will be

obvious that the hook-shaped slot will likewise be inverted from the position of Fig. 1; and in any case, this slot is preferably so shaped that its extreme ends will aline with each other longitudinally of the casing, thereby maintaining the conducting elements on the slide in proper alinement with the lamp and plug terminals connected by them. So also, the longer end of the hook-shaped slot is preferably extended beyond the position occupied by the handle 13 when the latter is nearest this end, as in Fig. 2, so as not to interfere with the firm contacting of the respectively contacting elements at this time.

I claim as my invention:

In a socket for a lamp having two terminals on its base, a casing equipped at one end for holding said base, an insulator rigidly held by the casing at some distance from the lamp base, an intermediary insulator slidably disposed in the casing between the lamp base and the aforesaid insulator, two pair of conducting elements carried respectively by the two insulators, coöperating means on the casing and the intermediate insulator for holding the latter with the conducting elements carried by the same out of contact with the terminals on the lamp base, and spring-pressed extension means carried by the conducting elements on one insulator and projecting toward those on the other insulator for continuously affording an electrical connection therebetween and for holding the intermediary insulator in its said locked position.

Signed at Chicago, Illinois, January 9th, 1917.

GEORGE C. KNAUFF.
